H. F. MARENDAZ.

HOSE PROTECTOR.

APPLICATION FILED AUG. 24, 1908.

913,903.

Patented Mar. 2, 1909.

UNITED STATES PATENT OFFICE.

HENRY FRANCIS MARENDAZ, OF WATERBURY, CONNECTICUT, ASSIGNOR OF ONE-HALF TO CHARLES HENRY REGAN, OF WATERBURY, CONNECTICUT.

HOSE-PROTECTOR.

No. 913,903.

Specification of Letters Patent.

Patented March 2, 1909.

Application filed August 24, 1908. Serial No. 450,028.

To all whom it may concern:

Be it known that I, HENRY FRANCIS MARENDAZ, a citizen of the United States, residing at Waterbury, in the county of New Haven and State of Connecticut, have invented new and useful Improvements in Hose-Protectors, of which the following is a specification.

My invention relates to hose protectors. During the operation of blacking or polishing shoes, particularly those of the low-cut variety, much annoyance is caused by the blacking or polish being accidentally applied above the edge of the upper on the hose or stocking of the wearer.

The present invention has for its object the provision of a protector designed to be applied inside the shoe to prevent the blacking or polish from getting on the wearer's hose, and seeks to obviate the defects of earlier protectors and to provide advantages thereover by the provision of a protector made in a single piece of novel shape or construction, which will protect the hose both at the back and front, which are the points where the blacking or polish is most likely to get on the hose, as well as the sides thereof, which will be adapted to carry out its purpose, regardless of the length of the tongue on the shoe, my protector having means especially designed to protect hose where the shoe tongue is short and does not afford adequate protection at the front, but in addition to this, the present invention, by the provision of a one-piece protector, prevents any catching of the polishing cloth, and the invention further aims to provide a protector which can be rapidly and easily adjusted to any shoe and ankle and secured in position.

A further object is to provide a protector of the class set forth which will be of such simple construction that it may be so cheaply sold as to be within the reach of all boot-blacks.

The most perfect embodiment of the invention which I have at this time devised is set forth fully hereinafter and the novel features of the invention are recited in the appended claim.

In the accompanying drawings: Figure 1 is a perspective showing the invention in use;

Fig. 2, a detail face view of the protector as it appears when spread out; and Fig. 3, a section on line 3—3 of Fig. 2.

55

The protector 1 is made from a single piece of any suitable flexible material, celluloid being preferred, which has lobes 2 at its lower part to fit into the sides of the shoe around the ankle, said lobes being defined by edges 60 which, starting at the point 3 diverge as curves and rise again adjacent the ends of the protector, whereat the rounded tongues 4 are provided. The upper end parts of the protector are curved at 5 to cause the device to 65 comfortably dispose itself at the front of the ankle, beside giving it a neat appearance when used. Strings 6 are connected to the end parts of the protector at 7, an efficient, simple and cheap connection being that 70 shown, the holes 8 receiving the ends of the strings which are laced therethrough, the extremities 9 being bound in position by the pressure of the inner part of the string thereon.

When the protector is applied, the lobes 2 75 are slipped down inside the shoe at the sides of the ankle and the point 3 then constitutes a notch or crotch which receives the ankle at the back, and the tongues 4 are disposed back of the tongue of the shoe. The strings 80 may then be tied in the ordinary fashion and those on the shoe engaged therewith as shown in Fig. 1 and the protector is thus held in position around the ankle and inserted within the shoe in such fashion that any blacking 85 or polish which would otherwise tend to get on the hose is received on the outer face of the protector.

The lobes 2 securely retain the protector in position and the tongues coöperate with the 90 shoe tongue to prevent the protector from rising or flaring outwardly at that point, beside being of particular advantage on shoes which have a very short tongue. Being in one piece, there are no projecting parts to 95 catch the polishing cloth or brush, while the employment of the strings enables the user to secure the protector firmly in position, regardless of the size of the shoe or the user's ankle.

Having thus described my invention, what I claim as new and desire to secure by Letters Patent, is:—

The herein described hose protector com-

100

posed of a single piece of flexible material having lobes adapted to enter the shoe at the sides of the ankle and provided with tongues on its free ends adapted to be positioned against the tongue of the shoe, and means for connecting the free ends of the protector.

5 In testimony whereof I have signed my

name to this specification in the presence of two subscribing witnesses.

HENRY FRANCIS MARENDAZ.
